(57) **CLAIM**

The ornamental design for a label printer, as shown and described.

DESCRIPTION

FIG. 1 is a perspective view of a label printer showing our new design;

FIG. 2 is another perspective view of FIG. 1;

FIG. 3 is a front view of FIG. 1;

FIG. 4 is a rear view of FIG. 1;

FIG. 5 is a first side view of FIG. 1;

FIG. 6 is a second side view of FIG. 1;

FIG. 7 is a top view of FIG. 1; and,

FIG. 8 is a bottom view of FIG. 1.

The broken lines shown in the Figures are for the purposes of illustrating portions of the label printer, which form no part of the claimed design.

1 Claim, 8 Drawing Sheets
